& Co. Limited, Leicester, England, a company
of Great Britain

Application October 13, 1942, Serial No. 461,876
In Great Britain October 16, 1941

19 Claims. (Cl. 66—146)

This invention relates to means for controlling yarns in knitting machines, and has reference to mechanism for use in connection with the supply of two or more yarns simultaneously to the needles, as for example a main yarn and a splicing yarn, for controlling such yarns when, by reason of some variation in the knitting operation, the tension thereon is relaxed.

The present invention is primarily intended for application to circular independent needle seamless hosiery knitting machines, for taking up slack in the main and splicing yarns during reciprocating knitting to produce heel and toe pouches.

The invention is also applicable for use in connection with feeding arrangements wherein a main yarn and a splicing yarn are introduced to the needles separately, as distinct from arrangements whereby the splicing yarn is run in with the main yarn, either by frictional contact therewith or by being twisted round it. In this connection it is sometimes desired to use a splicing yarn which is weaker than the main yarn, and the object of the present invention is to enable this desideratum to be achieved.

The invention accordingly comprises a controlling or take-up mechanism for separate yarns wherein the yarn engaging members are so constructed, arranged and controlled as to be adapted for use in connection with yarns of different strengths, e. g., a splicing yarn weaker than the main yarn, with less risk of breaking the weaker yarn.

Some illustrative constructional examples of the invention applicable to a circular seamless hosiery machine as a take-up mechanism for a main yarn and a splicing yarn, will now be described with reference to the accompanying drawings, wherein,

Figure 1 is a plan view of a yarn controlling or take-up mechanism the yarn engaging members of which are carried respectively by arms of different lengths coupled together and pivotally mounted on different pivots.

Figure 2 is a side elevational view of the same as seen in the direction of the arrow A in Figure 1.

Figure 3 is a side view of a lever employed for holding the take-up members inoperative at required times.

Figure 4 is a plan view of a modification wherein the yarn controlling or take-up members are mounted on a pivot common to both.

Figure 5 is a side elevational view of the same as seen in the direction of the arrow B in Figure 4.

Figure 6 is a detail part sectional view, taken on the line VI—VI of Figure 4, illustrating more clearly the yarn tensioning means combined with the said modified yarn controlling or take-up arrangement, and

Figures 7 and 8 are plan and side views respectively of a still further and particularly simple form of the invention.

Like parts are designated by similar reference characters throughout the drawings.

Referring to Figures 1 and 2, the take-up mechanism therein depicted includes two take-up members 1 and 2 consisting of rods or wires formed or, as shown, provided with yarn guiding eyes 3 at one end and carried by arms 4 and 5 of different lengths coupled together, scissor-wise, between their ends by means of a pin 6 and slot 7. The arms 4 and 5 are pivotally mounted horizontally one above the other on pins 8 and 9 inserted vertically in spaced relation in a bracket 10 or a like support so that the pivot 8 for the longer arm 4 is located further away from the couplings 6, 7 than the pivot 9 for the shorter arm 5. The shorter arm is pivoted at one end, whereas the other arm is pivoted between its ends. Conveniently the bracket 10 is slotted for reception of the arms 4 and 5 and the pivot pins 8 and 9 are inserted into upper and lower portions of the bracket respectively, as shown more clearly in Figure 2. The longer arm 4 has a controlling tension spring 11 connected to it. As depicted in Figure 1, the bracket 10 is mounted on an adjacent fixed part 12 of the machine so that the take-up members 1 and 2 extend generally towards the yarn feeding location C in the direction of a tangent to the needle circle nc—or substantially so. The total length of the take-up member 1 for the main yarn y exceeds the total length of the take-up member 2 for the splicing yarn y¹ so that the guiding eye for the main yarn is located further from the coupling 6, 7 than the guiding eye for the splicing yarn. The two yarns y and y¹ are fed to the needles 13 through two separate guides 14 and 15 located between the needles and the take-up members 1 and 2. When the yarns are being drawn upon by the needles 13 the take-up members are moved toward the needles against the action of the controlling spring 11 to a position in which they are disposed immediately one above another in parallel relation, but when the pull on the yarns is relaxed the take-up members are moved away from the needles by the said spring and at the same time have limited relative pivotal movement so that they become angularly disposed relatively to each other in the manner indicated in dot-and-dash lines in Figure 1. By reason of this compound arrangement of the yarn engaging members the main yarn y takes the stress or the greater part of the stress engendered by the movement of the said members against the action of the spring 11 when the yarns are being pulled by the needles 13, but both of the said members take up the same amount of slack when the pull on the yarn is relaxed.

For tensioning the yarns between the bobbins or other source of supply when the take-up members 1 and 2 operate, there are provided yarn trapping members comprising parallel rods or bars such as 16 and 17 one or each movable in relation to the other, and an intermediate resilient wire, blade, or spring pressed member such as 18. The rods or bars are normally held in contact with each other by a spring or springs. In the specific construction and arrangement illustrated in Figures 1 and 2 the rod or bar 16 is pivoted on a pin 19 at one end and the rod or bar 17 is fixed at the corresponding end in the bracket 10 so as to extend horizontally therefrom in the same direction as the take-up members 1 and 2, but at a higher level. The pivoted rod or bar 16 is influenced by a compression spring 20 inserted in the bracket. This spring is arranged to act upon the end of the rod or bar 16 near the pivot 19, whereby the said rod or bar is normally caused to press upon the fixed rod or bar 17. The intermediate member 18 in this example consists of a blade spring attached to the pivoted rod or bar 16 so as normally to press on the fixed rod or bar 17. The rods or bars together serve to trap one of the yarns (in this case the main yarn y), whereas the intermediate member 18 and the fixed rod or bar 17 serve to trap the other, i. e., splicing yarn y^1 . As will be clear from a consideration of Figure 1, the yarns y and y^1 extending from the bobbins or like source are passed through the tensioning means before being engaged with the take-up members 1 and 2. Provision of any suitable character is made for opening the tensioning means against the action of the spring 20 when the take-up members 1 and 2 are pulled towards the needles 13 so as to permit the yarns to run freely, and the tensioning means are automatically closed upon movement of the take-up members away from the needles when the pull on the yarns is relaxed. Conveniently, for this purpose, the tensioning means are positioned suchwise as to be acted upon by the take-up arrangement. To this end, in the example illustrated, the pivoted rod or bar 16 is provided with a lug or similar projection 16a which is so located as to be acted upon by the longer arm 4 whereby as the take-up members are moved towards and away from the needles 13 the tensioning means are automatically opened and closed.

For holding the take-up members and the tensioning means inoperative at required times, e. g., during circular knitting and all round splicing, mechanism adapted for action upon the take-up members and controlled from the timing chain or drum of the machine is provided. In this respect the tensioning means and the take-up members may be controlled independently, but when the tensioning means are controlled by the take-up arrangement, as hereinbefore described, it is convenient to employ mechanism common to both, e. g., associated with the take-up members. Thus, according to a simple example, applicable to the take-up arrangement and tensioning means just described, a catch lever 21 is pivoted at 22 between its ends on the support 12 with its operative end 21a directed towards the longer arm 4 of the take-up arrangement. A spring 23 is connected to the catch lever whereby the latter is turned so that its operative end opposes the arm 4. Although, merely for convenience in illustration, the spring controlling the catch lever is depicted in Figure 2 as being

a tension spring, it is to be understood that any other form of spring or springs suitably arranged to achieve the same result may be adopted. For instance, a torsion spring associated with the pivot 22 would be eminently suitable for this purpose. The tail end 21b of the catch lever 21 is opposed to a collar 24 on a push rod 25 (see Figure 1) suitably guided in the machine in association with the timing chain or drum (not shown). Thus, when the take-up members 1 and 2 are moved towards the needles 13, the catch lever 21 springs into contact with the arm 4 and holds the take-up members in this position so long as the push rod is not operated. The catch lever is tripped to release the take-up members by an appropriate cam on the chain or drum acting through the push rod 25 and the collar 24. The operative end 21a of the catch lever is formed with a stop 21c for contact with the underside of the arm 4 to limit movement of the lever under the influence of the associated spring 23. As will be understood, when the take-up members 1 and 2 are thus held, the tensioning means are also opened as hereinbefore described and held in this condition until the catch lever is tripped. If desired, the operative end of the catch lever may be formed, as shown in Figure 3, with a convex cam edge, in which instance the said lever may be arranged to act with camming action on the inner edge of the arm 4 suchwise as to take the pull of the spring 21 and thus relieve tension on the yarns y and y^1 .

The modified constructional form of the invention illustrated in Figures 4 and 5 includes a shorter take-up member 26 for the main yarn, and a longer member 27 for the splicing yarn, the two members being located one above the other as shown in Figure 5. The take-up member 26 consists of a rod or wire which is provided with a yarn guiding eye 28 and carried by an arm 29. Similarly, the member 27 consists of a rod or wire provided with a yarn guiding eye 28' and carried by an arm 30 which is somewhat longer than the arm 29. The two members 26 and 27 are pivotally mounted on a pin 31 fixed in a bracket 32. As shown in Figure 4, the shorter arm 29 is formed with a lug 29a for the connection thereto of one end of a tension spring 33 the other end of which is connected to a lug 34 on a rod 35 fixed adjacent to the take-up members. Between the arms 29 and 30 is a collar or boss 36 for the reception of a torsion spring 37. One end 37a of this spring is connected to a sector 38 which is mounted on the pivot pin 31 and adjustably clamped to the shorter arm 29 by means of a screw 39 passed through a slot 38a in the sector; the other end 37b of the said torsion spring is engaged with the longer arm 30 so that the two take-up members 26 and 27 are in effect yieldably coupled together as hereinbefore mentioned. By slackening the screw 39, adjusting the sector 38, and thereafter tightening the screw to secure the sector, the strength of the torsion spring 37 can be varied according to requirements. Thus, when the take-up members are rendered operative, as hereinbefore described, the tension spring 33 is the main take-up spring and the torsion spring 37 applies individual tension to the splicing yarn, keeping this under an even tension which can be reduced to a minimum by appropriate adjustment of the last mentioned spring. The said members can also move relatively, if necessary, while working.

For holding the take-up members 26 and 27 inoperative at required times, there is provided a pivoted catch lever 21 operated in a similar way to the corresponding lever in the first described example. In the present example, however, the catch lever is straight instead of being cranked and is adapted for action upon tail-like extensions 29b and 30a formed on the shorter and longer arms 29 and 30 respectively.

A modified form of the means for tensioning the yarns between the bobbins or other source of supply and the needles, when the take-up members operate, may also be provided in lieu of those hereinbefore specifically described. This modification, which is illustrated in Figures 4, 5 and 6, comprises a short fixed bar 40 and two eccentrics 41 and 42 (one for each yarn) peripherally opposed to the fixed bar suchwise as to co-operate therewith. The two eccentrics are mounted to turn on the fixed rod 35 adjacent to the guiding ends of the take-up members 26 and 27. The fixed bar 40 extends between and is carried by the lug 34 and another similar element 43 secured upon the rod 35 in suitable spaced relation. The eccentrics may be controlled by a spring or springs or counterweighted so as to cause them normally to press on the opposing bar 40. Conveniently, and as shown, each eccentric is fitted with a part 44 formed with a guiding eye 45 which part serves as a counterweight, and the yarns from the bobbins or other source of supply are threaded through the eyes 45 before being passed between the eccentrics 41 and 42 and the bar 40 and engaged with the controlling or take-up members 26 and 27. Appropriate means are provided for rotating the eccentrics so that the trapping means are opened to permit the yarns to run freely when the take-up members are pulled towards the needles, or are held inoperative, and the trapping means are closed by reverse rotation of the eccentrics under the action of the associated spring or springs or the weight or weights. For this purpose—in the specific arrangement illustrated—the eccentrics 41 and 42 are coupled together by a pin 46, and the eccentric 42 is provided with a radial stud 47 to be acted upon for turning the eccentrics. This will be clearer from a consideration of Figures 5 and 6. A lever 48 is provided adjacent to the eccentrics for action upon the stud 47 and this lever is pivoted at 49 beneath a small block 50 carried by the fixed rod 35 and placed either directly or indirectly under the control of the timing chain or drum of the machine. Preferably the tail end 48a of the said lever is shaped in the manner depicted in Figure 5 for engagement by the shorter arm 29 whereby, when the take-up member 26 is held inoperative, the lever 48 is held in contact with the stud 47 and the eccentrics 41 and 42 are maintained in the open position. When the take-up members are released and move away from the needles, the lever 48 is likewise released and thus permits the eccentrics to turn to the closed position. In Figure 6, the eccentric 42 is shown in the closed position with the main yarn y trapped between it and the opposing bar 40. Upon reverse movement of the take-up members under the pull of the yarns, the lever 48 is operated and turns the eccentrics so that the yarns are again freed. By reason of this arrangement the trapping means are operated by the take-up member 26 for the main yarn so that the take-up member is relieved of all effort in this respect

and is merely subject to the resistance offered by its spring.

It is to be clearly understood that the modified trapping means just described are not necessarily restricted in use to association with the particular take-up arrangement illustrated in Figures 4 and 5. They may be used in combination with any suitable arrangement of yarn controlling or take-up members constructed in accordance with this invention. For instance, they may with advantage be employed together with a take-up arrangement similar to that shown in Figures 1 and 2—in lieu of the relatively movable rods or bars 16 and 17 and the intermediate resilient member 18.

A further and particularly simple example of the improved take-up arrangement is shown in Figures 7 and 8. As will be seen, this arrangement comprises a single pivoted arm 51 serving to carry both of the take-up rods or wires 52 and 53. The shorter rod or wire 52 is for the main yarn, while the longer rod or wire 53 is for the splicing yarn. The common pivoted arm 51 is formed with a lug 51a for connection to a controlling tension spring 54, and also with a tail-like extension 51b for co-operation with a catch lever of the character and for the purpose hereinbefore described. The shorter take-up rod or wire 52 is rigidly fixed within the arm 51, whereas the longer rod or wire 53 is pivotally mounted upon a pin 55 secured in the said arm. The longer rod or wire, moreover, is made to some extent resilient by reason of being coiled at its inner end 53a about the pivot pin 55 to provide what is in effect, or the equivalent of, a torsion spring. In this way individual tension is applied to the splicing yarn. As will be understood, the arrangement is such that the two rods or wires are in effect yieldably coupled together and can therefore move relatively, if necessary, while moving towards and from the needles about the main pivot 56. Movement in either direction of the longer rod or wire 53 in relation to the shorter rod or wire 52 is, however, limited. To this end the rod or wire 53 may, as shown, conveniently extend through a closed lateral loop 57 formed integrally with the rod or wire 52. Thus, relative movement of the rod or wire 53 in either direction will be arrested by reason of it coming into contact with the appropriate side of the loop.

The take-up arrangement of Figures 7 and 8 may be used in combination with yarn trapping means of either of the forms hereinbefore specifically described.

A yarn controlling or take-up arrangement of the improved form may be used in conjunction with means of any form usually employed in knitting machines for supplying a main yarn and a splicing yarn separately to the needles. Moreover, such an arrangement may be employed in combination with splicing mechanism of the character described in the specification of our co-pending application Ser. No. 459,996.

The invention is applicable to circular independent needle knitting machines, plain and rib, including those of the double axially opposed, e. g., superimposed, cylinder type, to machines of the stationary cylinder type as well as to machines of the rotary cylinder type, and to multi-feeder machines as well as to single feeder machines, having either latch or bearded needles, and requiring mechanism for controlling yarns at the feeder or at any one or more or each of the feeders, as hereinbefore mentioned.

By suitable adaptation, and arrangement of controlling means, the invention may also be applied to flat knitting machines of the independent latch or bearded needle type.

What we claim then is:

1. For a knitting machine, yarn controlling mechanism comprising, in combination, a take-up member for a yarn, a second take-up member for a weaker yarn, a coupling connecting said members suchwise as to render them capable of limited relative movement, as well as movement together towards and from the needles of said machine, and separate pivots upon which the take-up members are mounted, said pivots being located at respectively different distances from the coupling, for the purpose herein specified.

2. For a knitting machine, yarn controlling mechanism comprising, in combination, a take-up member for a yarn, a second take-up member for a weaker yarn, two arms of different lengths by which the take-up members are respectively carried, a coupling whereby said arms are connected together between their ends so as to be capable of limited relative turning movement, and two different pivots upon which said arms are pivotally mounted for movement towards and from the needles of said machine, the pivot of the longer arm being located further from the coupling than the pivot of the shorter arm.

3. For a knitting machine, yarn controlling mechanism comprising, in combination, a take-up member for a yarn, at least one other take-up member for a weaker yarn, a common pivot about which said take-up members are both mounted for movement together towards and from the needles of said machine, and means for so controlling said members as to enable them to be loaded differently, for the purpose herein specified.

4. For a knitting machine, yarn controlling mechanism comprising, in combination, a take-up member for a yarn, at least one other take-up member for a weaker yarn, a common pivot about which said take-up members are both mounted for movement together towards and from the needles of said machine, and a spring arrangement between said members whereby the latter are yieldably coupled together and thus capable of limited relative movement under working conditions, for the purpose herein specified.

5. For a knitting machine, yarn controlling mechanism comprising, in combination, a take-up member for a main yarn, a second take-up member for a weaker yarn, a common pivot about which said take-up members are both mounted for movement together towards and from the needles of said machine, a spring of a given strength for controlling the first mentioned take-up member, and an adjustable spring for controlling the second take-up member whereby the load thereon can be varied according to requirements, the arrangement of the adjustable spring being such that said members are yieldably coupled together and thus capable of limited relative movement under working conditions, for the purpose herein specified.

6. For a knitting machine, yarn controlling mechanism comprising, in combination, a take-up member for a main yarn, a second take-up member for a weaker yarn, a common pivot about which said take-up members are both mounted for movement together towards and from the needles of said machine, a tension spring for controlling the first mentioned take-up member

and against the action of which both take-up members are moved towards the needles when the yarns are being drawn upon by the latter, and vice versa, and an adjustable torsion spring

5. for controlling the second take-up member whereby the load thereon can be varied according to requirements, the arrangement of said torsion spring being such that said members are yieldably coupled together and thus capable of limited relative movement under working conditions, for the purpose herein specified.

7. For a knitting machine, yarn controlling mechanism comprising, in combination, a take-up member for a yarn, a second take-up member for a weaker yarn, two arms of different lengths by which the take-up members are respectively carried, a coupling whereby said arms are connected together between their ends so as to be capable of limited relative turning movement, two different pivots upon which said arms are pivotally mounted for movement towards and from the needles of said machine, the pivot of the longer arm being located further from the coupling than the pivot of the shorter arm, and a controlling spring in connection with the longer arm and against the action of which the take-up members are moved towards the needles when the yarns are being drawn upon by the latter, and under the action of which said members move away from the needles when the pull of the yarns is relaxed.

8. At a yarn feeding location in a knitting machine, yarn controlling mechanism comprising, in combination, a take-up member for a yarn, a second take-up member for a weaker yarn, said members being horizontally disposed so as to extend towards the yarn feeding location in a direction transversely to the needles, a coupling connecting said members suchwise as to render them capable of limited relative movement, as well as movement together towards and from the needles of said machine, and separate vertical pivots upon which the take-up members are mounted, said pivots being located at respectively different distances from the coupling, for the purpose specified.

9. At a yarn feeding location in a knitting machine, yarn controlling mechanism comprising, in combination, a take-up member for a yarn, a second take-up member for a weaker yarn, said members being horizontally disposed so as to extend towards the yarn feeding location in a direction transversely to the needles, a common vertical pivot about which said take-up members are both mounted for movement together towards and from the needles of said machine, and means for so controlling said members as to enable them to be loaded differently, for the purpose herein specified.

10. For a knitting machine, mechanism for controlling separate yarns from a source of supply, said mechanism comprising, in combination, a take-up member for a yarn, at least one other take-up member for a weaker yarn, means whereby said members are coupled together suchwise as to adapt them for limited relative movement, as well as movement together towards and from the needles of said machine, and means for tensioning the yarns passing between the take-up members and the source of supply when said members are in operation so that the latter function to take up the slack between the needles and the tensioning means.

11. For a knitting machine, yarn controlling

mechanism comprising, in combination, a take-up member for a yarn, at least one other take-up member for a weaker yarn, means whereby said members are coupled together suchwise as to adapt them for limited relative movement, as well as movement together towards and from the needles of said machine, and means for holding the take-up members inoperative at required times.

12. For a knitting machine, mechanism for controlling separate yarns from a source of supply, said mechanism comprising, in combination, a take-up member for a yarn, at least one other take-up member for a weaker yarn, means whereby said members are coupled together suchwise as to adapt them for limited relative movement, as well as movement together towards and from the needles of said machine, means for tensioning the yarns passing between the take-up members and the source of supply when said members are in operation so that the latter function to take up the slack between the needles and the tensioning means, and means for simultaneously holding the take-up members and the tensioning means inoperative at required times.

13. For a knitting machine, yarn controlling mechanism comprising, in combination, a take-up member for a yarn, a second take-up member for a weaker yarn, two arms of different lengths by which the take-up members are respectively carried, one of said arms having a pin between its ends engaging in a slot formed in and between the ends of the other of said arms whereby the arms are coupled together scissorwise so as to be capable of limited relative turning movement, and two different pivots upon which said arms are pivotally mounted for movement towards and from the needles of said machine, the pivot of the longer arm being located further from the coupling than the pivot of the shorter arm.

14. For a knitting machine, yarn controlling mechanism comprising, in combination, a take-up member for a main yarn, a second take-up member for a weaker yarn, two arms of different lengths by which said take-up members are respectively carried, a common pivot upon which the arms are both pivotally mounted to enable said members to move together towards and away from the needles of the machine, a controlling tension spring in connection with the shorter arm, a boss between the two arms, a torsion spring which surrounds said boss and has one end thereof in engagement with the longer arm, a sector pivotally mounted upon the shorter arm and to which the other end of said torsion spring is connected, and means for adjustably clamping said sector to the shorter arm, the arrangement being such that the take-up members are yieldingly coupled together and thus capable of limited relative movement under working conditions, for the purpose herein specified.

15. For a knitting machine, yarn controlling mechanism comprising, in combination, an arm, a pivot upon which said arm is pivotally mounted, a take-up member for a yarn, which member is fixed in said arm, a second take-up member for a weaker yarn, said second member being pivotally mounted upon the arm, and spring means for so controlling the said arm and the second take-up member as to enable them to be loaded differently, the arrangement being such that the take-up members are capable of relative movement, as well as movement together towards and from the needles of the machine, for the purpose herein specified.

16. For a knitting machine, mechanism for controlling separate yarns from a source of supply, said mechanism comprising, in combination, a take-up member for a yarn, at least one other take-up member for a weaker yarn, means whereby said members are coupled together suchwise as to adapt them for limited relative movement, as well as movement together towards and from the needles of said machine, and means for tensioning the yarns passing between the take-up members and the source of supply when said members are in operation so that the latter function to take up the slack between the needles and the tensioning means, said tensioning means being constituted by a yarn trapping arrangement comprising two relatively movable and parallel trapping bars, spring means for normally holding said bars in contact with each other, a resilient trapping member arranged between said trapping bars, and means for opening the trapping arrangement against the action of the spring means to free the yarns when the take-up members move towards the needles, the trapping arrangement closing upon movement of said take-up members away from the needles when the pull on the yarns is released.

17. Yarn controlling mechanism according to claim 16, wherein the trapping bars are positioned suchwise as to be influenced by and opened at appropriate times by one of the take-up members.

18. For a knitting machine, mechanism for controlling separate yarns from a source of supply, said mechanism comprising, in combination, a take-up member for a yarn, at least one other take-up member for a weaker yarn, means whereby said members are coupled together suchwise as to adapt them for limited relative movement, as well as movement together towards and from the needles of said machine, and means for tensioning the yarns passing between the take-up members and the source of supply when said members are in operation so that the latter function to take up the slack between the needles and the tensioning means, said tensioning means being constituted by a yarn trapping arrangement comprising a fixed bar, two eccentrics peripherally opposed thereto suchwise as to cooperate therewith, loading means for controlling the eccentrics and causing the latter normally to press on the opposing bar for trapping the yarns, and means for rotating the eccentrics so that the trapping arrangement is opened to free the yarns when the take-up members move towards the needles, the trapping arrangement being adapted to close to trap said yarns upon reverse rotation of the eccentrics under the influence of the associated loading means.

19. In a knitting machine, in combination, a series of needles, and means for feeding two separate yarns of definitely different strengths conjointly to the said needles at the same feeder including yarn controlling mechanism comprising a take-up member for the stronger yarn, a second take-up member for the weaker yarn, means by which the take-up members are carried and on which they are capable of movement towards and from the needles, and a coupling whereby the said members are connected so as to be adapted for such movement together and also to be capable of limited relative movement while working.
